UNITED STATES PATENT OFFICE.

SADIE NOVER, OF NEW YORK, N. Y.

HANDBAG.

1,333,672.

Specification of Letters Patent. Patented Mar. 16, 1920.

Application filed March 28, 1919. Serial No. 285,918.

To all whom it may concern:

Be it known that I, SADIE NOVER, a citizen of the United States, and a resident of the borough of Manhattan, city, county, and 5 State of New York, have invented certain new and useful Improvements in Handbags, of which the following is a specification.

This invention relates to improvements in hand bags.

10 The invention has for one of its objects to provide a ladies' hand bag having two compartments or pockets one of which is normally closed and so formed that its existence and the means of access thereto cannot 15 be readily determined by a pickpocket.

A further object of the invention is to provide a hand bag having a body portion of fabric divided into two compartments of equal capacity and a metallic closure frame 20 formed of hinged sections, said body portion and frame sections being so constructed and arranged that the mouth of either compartment may be opened to an extent equal to the diameter of both outer frame sections.

25 In the accompanying drawings,

Figure 1 is a plan view of the hand bag opened, the mouth of the secret compartment being shown closed;

30 Fig. 2 a vertical sectional view, showing the mouths of both compartments partly open;

Fig. 3 an enlarged fragmentary vertical section showing the bag closed; and Fig. 4 an enlarged horizontal section through one 35 of the hinge connections of the metallic closure frame sections.

Referring to the drawings by numerals, 1 designates the body portion of the bag which may be formed of any suitable fabric or flexible material. The edges of the open 40 upper end of the body portion are secured in two rigid channel members 3 and 4 preferably formed of sheet metal. The channel members are formed with extensions or lugs 45 5 and 6, respectively, and are pivotally connected together by pivot pins 7 extending through apertures in said lugs. As shown, these channel members are of segmental form and when swung outwardly into the 50 same plane form a circular opening of considerable size permitting free access to the interior of the body portion. It will be obvious however that the channel members may have any other desired conformation.

55 The body portion 1 is divided into two compartments of equal capacity by a duplex

lining 2 in the form of two bags stitched together to form an intermediate partition or false wall 8 of double thickness. The lining may be made of silk or other suitable material and each bag 2 is preferably of substantially the same size as the body portion. The upper end of the partition or false wall 8 is confined and suitably secured in a channel member 9 having lugs or extensions 10 at its ends pivotally held to the hinge pins 7. The lower edge of the channel member 9 is flush with the lower edge of the outer wall of channel member 4 when the two members are in engagement and the inner wall of member 4 is cut away throughout its length at 4^a flush with the upper edge of member 9 which is substantially half as deep and wide as member 4 to adapt member 9 to be swung into engagement with member 4 with its inner wall substantially flush with the inner wall of member 4. The inner wall of member 4 is formed with a latch lug or projection 11 adapted to normally hold members 4 and 9 in engagement with each other, and a tab 12 is secured in member 9 to permit said member to be readily released when access is desired to the normally closed secret compartment. It will be observed that the outer wall of member 4 prevents the application of external pressure to member 9, thus preventing accidental separation of members 4 and 9. The usual small mirror with which hand bags of this type are usually equipped may be suspended from 90 the tab 12, if desired.

A combined suspending ring and clasp member 13 is secured to the closure frame section 4 and a coöperating clasp member 14, formed with a knob adapted to pass through 95 the ring 13 and frictionally lock the members 3 and 4 together, is held to member 3. It will be observed that members 3 and 4 may be freely opened and closed without separating members 4 and 9, and that member 9 100 and the partition or false wall 8 do not in any way interfere with free and unobstructed access to the compartment of which members 3 and 4 serve as closure frame sections. It will be observed also that either compartment may be filled to an extent equal to the full capacity of the bag since the false wall 8 will lie flush with either side of the bag, the area of the false wall being equal to half the area of the body portion 1. It will also 110 be seen that either sections 3 and 4 or sections 4 and 9 may be swung open into the

same plane to form an opening equal to the diameter of the closure frame, thus affording a large opening of maximum size to permit free access to either compartment of the bag. A suitable carrying strap or ribbon 15 is connected to the ring 13. Suitable spacing sleeves 16 are provided on the pivot pins 7 between the lugs 6 and 10 to maintain the frame sections 4 and 9 in proper relative positions. It will be obvious that the body portion and partition may be formed of single thickness if desired.

What I claim is:

1. A hand bag frame comprising a pair of main closure frame members of channel form having outer side walls of equal width, one of said channel members having an inner side wall of the same width as the outer side wall thereof and the other member having an inner side wall of less width than its outer side wall, an auxiliary closure frame member of channel form of less thickness and having side walls of less width than the outer side walls of the main frame members 25 and adapted to fit within the main frame member having the narrow inner side wall with the inner edges of its side walls flush with the inner edge of the outer wall of said main frame member, a pair of pivot pins 30 connecting the ends of all of the frame members together, means carried by the main frame members for releasably locking the main frame members together with the inner side walls thereof in abutting relation, and
  - means for releasably locking the auxiliary frame member within the main frame member having the narrow inner wall.
2. A hand bag comprising a main frame member of channel form, an auxiliary frame member of channel form and of smaller external dimensions than said main frame member and adapted to fit wholly within the same, means for releasably holding said auxiliary frame member within said main frame member to move therewith, a second main frame member of channel form and of the same thickness as the first-mentioned main frame member, said second main frame member having an inner side wall equal in width to the total width of the inner side walls of the other two frame members, means carried by the main channel frame members for releasably locking the main frame members together with the inner side walls thereof abutting against each other, means pivotally connecting the ends of all of said frame members together to swing about a common axis, a bag-like body portion having its upper edge confined in the channels of the main frame members, and flexible means in said bag-like body portion forming a partition dividing the body portion into two compartments, the edge of the upper portion of said flexible partition being confined in the channel in the auxiliary frame member.

This specification signed this twenty-seventh day of March, A. D. 1919.

SADIE NOVER.
